LOOM HARNESS

Frank H. Kaufmann, Huntington Valley, Pa., assignor to Steel Heddle Manufacturing Company, Philadelphia, Pa., a corporation of Pennsylvania

Filed Feb. 18, 1959, Ser. No. 794,030

8 Claims. (Cl. 139—88)

This invention relates to loom harness and more particularly to improved connections between the harness frames and the supporting and/or actuating parts of the harness.

It has heretofore been common practice in loom harness to provide supports intermediate the ends of the top rails of the loom harness frames. Such supports usually consisted of hooks or the like connected to or extending through the top rails of the harness frames. Such supports were difficult of access because of their locations. The distribution of the weight in harness frames supported intermediate their ends also tended to bend or stress the top rails so as to cause deformation thereof.

No suitable provisions have heretofore been available for connecting the supporting devices or actuating straps of the harness to the harness frames at the ends of the harness frames in a manner which would permit of adjusting the harness frames to level condition, or of raising or lowering the harness frames to a limited extent while still avoiding any tendency of the connectors or parts thereof to foul with adjoining harness frames or the supporting or actuating devices for the harness frames.

It is the principal object of the present invention to provide an improved mounting construction for harness frames which is carried on the ends of the harness frames so as to be readily accessible at the ends, and by which the forces between the harness frames and the harness are directly effective at the side struts of the harness frame.

It is a further object of the present invention to provide an improved connector for harness frames in which the connector forming part of the mounting structure is held against sidewise displacement or turning so as not to become entangled with adjoining harness frames or harness frame supporting or actuating devices.

It is a further object of the present invention to provide an improved connector carried on a loom harness frame which is held against turning or sidewise displacement and which is readily adjustable vertically at the end of the harness frame.

Other objects and advantageous features of the invention will be apparent from the description and claims.

The nature and characteristic features of the invention will be more readily understood from the following description taken in connection with the accompanying drawings forming part thereof, in which:

Figure 1 is a front elevational view of a loom harness frame embodying the main features of the present invention;

Fig. 2 is a fragmentary perspective view of a portion of one of the upper corners of the harness frame showing the details of construction of the connector in accordance with the present invention;

Fig. 3 is a fragmentary plan view of one end of the upper portion of a harness frame showing the connector of the present invention mounted thereon;

Fig. 4 is a fragmentary vertical sectional view taken approximately on the line 4—4 of Fig. 3; and

2

Fig. 5 is a fragmentary end elevational view of the structure shown in Fig. 4.

It should, of course, be understood that the description and drawings herein are illustrative merely, and that various modifications and changes can be made in the structure disclosed without departing from the spirit of the invention.

Like numerals refer to like parts throughout the several views.

10 Referring now more particularly to the drawings, in the embodiment of the invention illustrated, the top and bottom rails 10 and 11 of a loom harness frame are shown as connected at their ends by means of side struts 12 which may be of any preferred construction.

15 For example, the same may be made of two strips 12a and 12b secured to each other and having their respective ends bent at right angles as at 13 and 14 and secured on the inner and outer edge portions of the ends of the top and bottom rails 10 and 11 by screws 15.

20 The harness frame, in spaced relation to the top and bottom rails 10 and 11 can have upper and lower heddle supporting rods 16 mounted therein with their ends engaged in openings 17 in the side struts 12 and held against displacement along their longitudinal axes by resilient clips 18 mounted on the inner edges of the top and bottom rails 10 and 11. The clips 18 can have end portions 19 engaged in notches 20 in the heddle supporting rods 16.

25 The heddle supporting rods 16 can be provided, in the customary manner, with heddles 21 of the type made of thin flat strips of metal with mortices for mounting the heddles on the supporting rods and with central warp supporting eyes of well-known type.

30 The outer side strut strips 12a are provided, preferably at locations aligned with the inturned ends 13 of the inner strut strips 12b, with outwardly disposed horizontal projections 22 to which upwardly extending side strip portions 23 are connected and from which inturned horizontal projections 24, parallel to the projections 22, are connected as a continuous and integral part of the strut strips 12a.

35 The horizontal projections 22 and 24 on each side of the harness frame are provided with aligned openings 25 and 26 for the reception of the shank portion 27 of a hook 28. Nuts 29 and 30 are in threaded engagement with the shank portion 27 and thus adjustably engage respectively with the outer upper face of the projection 24 and the lower outer face of the projection 22 for permitting vertical adjustment of the shank 27 and for the locking of the shank 27 at the desired position of adjustment.

40 The hook 28 is provided with a stem portion 31 from which an upright portion 32 extends close to the strut strip 12a, and an outwardly and downwardly projecting portion 33 in the same plane as the hook portions 27, 31 and 32, and for disposition in a plane parallel to the main longitudinal plane of the top rail 10 for engagement of the supporting or actuating structure such as a spring, harness strap, or the like (not shown).

45 On the upper faces of the strut ends 14, holding strips 34 are secured and are preferably held in position by the same screws 15 which retain the strut ends 14 in engagement with the top rail 10. The holding strips 34 have a downwardly extending bifurcated end 35 parallel to the end of the top rail 10, with the bifurcations disposed on opposite sides of the upright portion 32 of the hook 28 to prevent the turning movement thereof.

50 It will be noted that the hook 28 can be adjusted vertically with respect to the top rail 10 by adjustment of the nuts 29 and 30 which nuts also serve to hold the hook 28 locked in adjusted position. The location of the hook 28 and the nuts 29 and 30 at the ends of the harness

frames provides easy access for adjustment. The hooks 28 are retained against turning by the engagement of the upright portions 32 in the bifurcated end 35.

The hooks 28 are also prevented from moving or turning to positions such that they could engage with adjoining harness frames or harness supports or actuators.

I claim:

1. In a loom harness, a loom harness frame having top and bottom rails and side struts connecting said rails, and actuating connections for the sides of said frame comprising a portion on at least one of each side struts extending sidewise beyond at least one end of one of said rails, a hook having a vertical shank extending through said strut portion, members in adjustable engagement with said shank and engaging said strut portion for determining the vertical positioning of said shank, and a member carried by said harness frame and engaging said hook, said last member permitting vertical positioning of said shank and restraining said hook against turning.

2. In a loom harness, a loom harness frame having top and bottom rails and side struts connecting said rails, and actuating connections for the sides of said frame comprising a portion on at least one of each of said side struts extending sidewise beyond one end of said top rail, a hook having a vertical shank extending through said strut portion and having a holding portion, members in adjustable engagement with said shank for determining the vertical positioning of said shank, and a member carried by said harness frame and engaging said holding portion of said hook and restraining said hook against turning.

3. In a loom harness, a loom harness frame having top and bottom rails and side struts connecting said rails, and actuating connections for the sides of said frame comprising a portion on at least one of each of said side struts extending sidewise beyond one end of said top rail, a hook having a vertical shank extending through said strut portion and a portion offset with respect to said vertical shank, adjustable members in engagement with said shank for determining the vertical positioning of said shank, and a member carried by said harness frame and engaging said offset portion of said hook and restraining said hook against turning.

4. In a loom harness, a loom harness frame having top and bottom rails and side struts connecting said rails, and actuating connections for the sides of the frame, at least one of said connections comprising an outwardly projecting portion on one of said side struts extending sidewise beyond the end of one of said rails, a hook having a vertical shank extending through said projecting portion, members in engagement with said shank and engaging said projecting portion for determining the vertical positioning of said shank, said hook having a holding portion thereon, and a member carried by said harness frame and engaging said holding portion and restraining said hook against turning.

5. In a loom harness, a loom harness frame having top and bottom rails and side struts connecting said rails, and actuating connections for the sides of the frame, at least one of said connections comprising an outwardly projecting portion on one of said side struts extending

sidewise beyond the end of one of said rails, a hook having a vertical shank extending through said projecting portion, adjustable members in engagement with said shank and engaging said projecting portion for determining the vertical positioning of said shank, said hook having an upright portion, and a member carried by said harness frame and engaging said upright portion and restraining said hook against turning.

6. In a loom harness, a loom harness frame having top and bottom rails and side struts connecting said rails, and actuating connections for the sides of the frame, at least one of said connections comprising an outwardly projecting portion on one of said side struts extending sidewise beyond the end of one of said rails, a hook having a vertical threaded shank extending through said projecting portion, adjustable locking members in engagement with said threaded shank and said projecting portion for determining the vertical positioning of said shank, said hook having an upright portion, and a member carried by said harness frame and engaging said upright portion and restraining said hook against turning.

7. In a loom harness, a loom harness frame having top and bottom rails and side struts connecting said rails, and actuating connections for the sides of the frame, at least one of said connections comprising spaced connected portions on one of said side struts extending outwardly from the end of one of said rails with vertically aligned openings therethrough, a hook having a vertical threaded shank extending through said openings, members rotatable on said shank and engaging opposite faces of said projecting portions for determining the vertical positioning of said shank, said hook having an inclined neck connected to said shank with an upright portion extending vertically therefrom, and a member secured to the outer edge of one of the rails of the harness frame and having a bifurcated end extending along the end of said rail and engaging said upright portion of said hook and restraining said hook against turning.

8. In a loom harness, a loom harness frame having top and bottom rails and side struts connecting said rails, and actuating connections for the sides of the frame, at least one of said connections comprising spaced connected portions on one of said side struts extending outwardly from the end of one of the rails with vertical aligned openings therethrough, a hook having a vertical shank extending through said openings, locking members in engagement with said shank and engaging opposite faces of said projecting portions for determining the vertical positioning of said shank, said hook having an inclined neck connected to said shank with a vertical portion extending therefrom, and a member secured to the outer edge of one of the rails of the harness frame and having a bifurcated end extending along the end of the said rail and engaging said vertical portion of said hook and restraining said hook against turning.
